SUPPORTING-ARM FOR RADIAL DRILLS.

1,086,691.

Specification of Letters Patent. Patented Feb. 10, 1914.

Application filed October 12, 1912. Serial No. 725,415.

To all whom it may concern:

Be it known that I, WILLARD T. SEARS, a citizen of the United States, residing at Hartford, in the county of Hartford and State of Connecticut, have invented certain new and useful Improvements in Supporting-Arms for Radial Drills, of which the following is a specification.

This invention relates to radial drills and more especially to the supporting arms thereof which sustain the spindle-carrying head. These supporting arms during work, are subjected to considerable twisting strains and various means have been provided heretofore, for resisting the same. One way of accomplishing this particular result has been to make the supporting arm in two laterally-spaced sections, the thrust resulting from the action of the drill being applied equally to these two sections. This is an ideal thrust-resisting arm and practically eliminates the evils resulting from torsion; it is objectionable, however, in that the mechanism for adjusting the head and the spindle, is situated some distance from the tool, making it quite unhandy for the operator who frequently has to shift his hands from said adjusting mechanism to the tool and vice versa. I provide a construction where I secure the advantage of a sectional type of supporting arm without the objection to which I have alluded, in that the adjusting mechanism is in close proximity to the tool.

In the drawing accompanying and forming part of the present specification I illustrate in cross section one of the several forms of embodiment of the invention which to enable those skilled in the art to practise the same will be fully set forth in the following description. I do not restrict myself to this disclosure; I may depart therefrom in several respects within the scope of the invention defined by the claims following said description.

A radial drill ordinarily comprises a vertical column and a horizontally-disposed arm extending therefrom, said arm supporting the adjustable head which carries the rotary drill-spindle. The arm shown in the drawings has the laterally-spaced or separated thrust-receiving sections 2 and 3, which as shown are hollow, an advantageous though not essential construction. As shown the section 2 is deeper than the com-

panion section 3, the tops of the two being preferably but not necessarily in horizontal alignment. The lower portion of the section 2 extends below the corresponding portion of the section 3 for a purpose that will be hereinafter explained. In the interval between the said two sections, the head 4 is situated, being provided with the vertically-disposed spindle 4'. Said head 4 is shown provided on one side thereof (the right as shown) with a rib or fin 5 fitted for horizontal sliding movement in the rabbit or groove 6 in the section 2, and confined therein by the removable gib 7. The opposite side of said head is equipped with an upwardly curved horn or projection 8, the terminal portion of which is flattened to engage and slide upon the flat bearing face or way 9, near the lower portion of the section 3. It will be observed that the bearing contact of the rib or fin 5 is a less distance from the center of upward thrust of the tool than is the bearing contact of the horn or projection 8, said center being coincident with the axis of rotation of the spindle 4'. Naturally therefore the amount of upward thrust applied to the section 3 is less than that applied to the section 2, and in practice the difference in thrust or leverage applied will correspond practically with the difference in vertical resisting power of the two sections of the supporting arm, the section 2 being of greater resisting power than the section 3. Owing to the fact that the lower portion of the section 3 is some distance above the corresponding portion of the section 2 I provide ample space in which to receive and accommodate the adjusting mechanism for the head 4 and spindle 4' and at the same time provide that such mechanism be closely adjacent to the tool or drill, thus materially simplifying and reducing the work of the operator.

While the two sections of the arm receive the upward thrust of the drill, transmitted thereto through the spindle 4', and head 4, said head in the construction shown (although not essential) is sustained wholly by or from the deeper and greater thrust-resisting section 2. The head 4 has the extension 12 of L shape, the pendent branch of which fits against the bearing surface 13 on said section 2 to prevent tipping of said head. It should be noted that while the dif-

ference in vertical thrust resisting power of the two sections of the arm is preferably obtained by making them of different depths, this may not always be necessary.

5 In the space immediately below the lower portion of the section 3 is located the adjusting arm or lever 10 fastened to the lower end of the shaft 11 carried by suitable bearing means on the head 4, the upper end of 10 said shaft being geared (although the gearing is not shown being quite common) to the spindle 4' for longitudinally adjusting said spindle. It will be seen that the distance between this arm or lever 10 and the tool end 15 of the spindle 4' is quite small.

What I claim is:

1. A supporting - arm for radial - drills, comprising two laterally-spaced sections of different depths, the section of greater depth 20 extending below the section of less depth, and a spindle-carrying head between said sections, having a thrust contact with both said sections, the point of thrust contact against the section of less depth being a 25 greater distance from the axis of rotation of the spindle than the point of thrust contact against the section of greater depth.

2. A supporting - arm for radial - drills, comprising two laterally-spaced sections of different depths, the upper portions of which 30 are approximately in horizontal alinement, the section of greater depth extending below the section of less depth, and a spindle-carrying head between said sections, having a

thrust contact with both said sections, the point of thrust contact against the section of less depth being a greater distance from the axis of rotation than the point of thrust contact against the section of greater depth.

3. A supporting arm for radial drills 40 comprising laterally spaced sections of different thrust-receiving ability, and a spindle-carrying head having a spindle between the sections of the arm, having a thrust contact with both sections, the points of thrust contact against said sections being disposed at such distance from the axis of the spindle as to cause said head to apply an upward thrust to each of said sections approximately in proportion with the thrust-receiving ability 50 thereof.

4. A supporting - arm for radial - drills, comprising laterally-spaced sections of different thrust-receiving ability, and a spindle-carrying head between the sections of the 55 arm, having a thrust contact with both sections, the point of thrust contact against the section of less thrust-receiving ability being a greater distance from the axis of rotation of the spindle than the point of thrust contact of the section of greater thrust-receiving ability.

In testimony whereof I affix my signature in presence of two witnesses.

WILLARD T. SEARS.
